UNITED STATES PATENT OFFICE.

THOMAS A. McCARTY, OF WASHINGTON, DISTRICT OF COLUMBIA, ASSIGNOR OF ONE-HALF TO WILLIAM G. CHANDLER, OF WASHINGTON, DISTRICT OF COLUMBIA.

ROLLING-PIN.

1,206,562.

Specification of Letters Patent. Patented Nov. 28, 1916.

Application filed May 10, 1916. Serial No. 96,580.

To all whom it may concern:

Be it known that I, THOMAS A. McCARTY, a citizen of the United States, residing at Washington, in the District of Columbia, have invented certain new and useful Improvements in Rolling-Pins; and I do hereby declare the following to be a full, clear, and exact description of the invention, such as will enable others skilled in the art to 10 which it appertains to make and use the same.

This invention relates to a rolling pin.

An object of the invention resides in the provision of a rolling pin in which the several parts which go to make up the pin may be used as various kitchen utensils such as funnels, biscuit-cutters, sieves, scoops and the like.

A further object of the invention resides 20 in so constructing the device that it will be simple to manufacture, easily operated and will be exceedingly handy for the various uses.

With these and other objects in view, such 25 as will appear as my description progresses, my invention comprises the combination and arrangement of parts as set forth in and falling within the scope of the appended claims.

30 In the drawing: Figure 1 is an elevational view of a device constructed in accordance with my invention; Fig. 2 is a longitudinal sectional view taken through the device when the parts are in their folded positions; 35 Fig. 3 is a fragmental sectional view showing the device in operation as a sieve for flour or the like; Fig. 4 is an elevational view partly broken away at one end and showing the element separated; Fig. 5 is 40 an enlarged detail of the scoop portion of the device, and Fig. 6 is a similar view of the biscuit cutter portion.

The embodiment of the invention illustrated in the drawing includes a hollow 45 cylindrical body portion 1 which is provided with a permanently mounted screen member 2 approximately midway between its ends and with a removably mounted screen member 3 of finer mesh mounted adjacent 50 to the member 2. The screen member 2 is maintained in place by a collar 2', which collar is secured to the body portion 1 and which together with the screen members 2 and 3, I hereinafter designate as a partition. 55 The collar 2' is arranged so that the end

of the extension 6 will engage therewith as illustrated in Fig. 2 of the drawing. An end piece which includes a cylindrical portion 4 and a neck or handle portion 5 is removably mounted in one end of the body portion 1 and an extension 6 is removably mounted in the portion 4 of this end piece and extends therefrom. This extension, when the portion 4 of the end piece is inserted in the body portion 1, contacts with the screen member 2 to limit the inward movement of the end piece so that it will be held in place and the handle portion 5 will be in position to be used. A frame which includes a collar 7, a U-shaped arm 8 having a bight portion and cross arms 9 having upturned ends 10 is removably mounted in the body portion to the side opposite to which the end piece, previously described is mounted. A second end piece which includes a cylindrical portion 11 and a handle or neck portion 12 is removably mounted in the end of the body portion 1 opposite to the previously described end piece. A screen 13 is mounted in the cylindrical portion 11 as is also a screen 14 which latter is mounted in the cylindrical portion 4. A collar 15 is mounted concentrically and within the cylindrical portion 11 of the end piece and is held in place by braces 16. When 80 the end piece comprising the portions 11 and 12 is inserted into the body portion 1 the inner edge thereof will engage the collar 7 and the arms 8 and 9 will engage the screen members 2 and 3 so that the inward movement of the end piece will be arrested and consequently it will be maintained in such position that the portion 12 may be used as a handle. 85

Now it will be obvious that the end pieces 90 may be removed and that the extension 6 together with the end piece to which it is attached may be used as a scoop or this extension may be removed from the end piece and the latter used as a funnel. Furthermore the opposite end piece may be used either as a funnel or, because of the presence of the collar 15, it may be used as a biscuit cutter. Furthermore the body portion 1 may be put in a vertical position with the frame 100 which includes the collar 7 in place therein and used as a sieve for flour or the like, the frame being used as an agitator. To facilitate the movement of this frame, I have provided the same with a keeper 17 in which a 105

handle 18 may be inserted so that it may be turned. Of course the removable sieve 3 may be taken from the body portion if desired.

5 Now it will be seen that I have provided a rolling pin wherein a body portion and two end pieces are provided and wherein means is provided for limiting the inward movement of the end pieces into the body portion.

10 While I have illustrated and described a particular embodiment of my invention, it has merely been for the sake of convenience and I do not wish to be limited to that particular embodiment as it is obvious that numerous changes may be made in the details of construction without departing from the spirit of the invention or exceeding the scope of the appended claims.

15 What I claim is:—

20 1. In a rolling pin, the combination with a cylindrical body portion, of end pieces removably mounted therein, a partition mounted in the body portion and means engageable with the end pieces and with the partition to limit the inward movement of the end pieces into the body portion.

25 2. In a rolling pin, the combination with a cylindrical body portion having a partition between its ends, of an end piece including a cylindrical portion and a tubular

30 handle portion, the cylindrical portion being adapted to be inserted in the body por-

tion, a substantially cylindrical extension removably mounted in the end piece and adapted to engage the partition to limit the inward movement of the end piece and a second end piece mounted in the other end of the body portion.

35 3. In a rolling pin, the combination with a cylindrical body portion having a partition between its ends, of an end piece removably mounted in one end of the body portion, means for limiting the inward movement of the end piece into the body portion including a collar, a U-shaped arm 40 and a cross arm mounted on the right portion of the U-shaped arm, which right portion and cross arm contact with the partition and an end piece mounted in the opposite end of the body portion.

4. A device of the class described including a hollow cylindrical body portion having a screen member in spaced relation to one end thereof, end pieces removably mounted in said body portion and an agitator rotatably mounted within the body portion and arranged to limit the inward movement of one end piece.

50 In testimony whereof, I affix my signature, in the presence of two witnesses.

THOMAS A. McCARTY.

Witnesses:

CLAUDE C. COLLINS,
CHAS. GREEN.
